(57) **CLAIM**

The ornamental design for an anchor pin for securing bedskirts, as shown and described.

DESCRIPTION

FIG. 1 is a Front elevational view of a anchor pin showing my new design:

FIG. 2 is a left side view thereof:

FIG. 3 is a top elevational view thereof:

FIG. 4 is a left side, bottom perspective view thereof:

FIG. 5 is a right side elevational view thereof; and,

FIG. 6 is a left side, top perspective view I claim.

The broken lines are for illustrative purposes and form no part of the claimed design.
